UNITED STATES PATENT OFFICE.

BENJAMIN F. WILLIAMS, OF GRAND RAPIDS, MICHIGAN.

SAFETY APPARATUS FOR RAILWAY-CARS.

1,141,737.

Specification of Letters Patent.

Patented June 1, 1915.

Application filed July 17, 1914. Serial No. 851,587.

To all whom it may concern:

Be it known that I, BENJAMIN F. WILLIAMS, a citizen of the United States, residing at Grand Rapids, in the county of Kent 5 and State of Michigan, have invented new and useful Improvements in Safety Apparatus for Railway-Cars, of which the following is a specification.

This invention relates to improvements in 10 safety apparatus for railway cars and has particular application to safety apparatus for use on railway mail cars and the like.

In carrying out the present invention, it 15 is my purpose to provide safety apparatus of the class described which will be found especially useful in conjunction with railway mail cars and other cars carrying money or articles of value and whereby the door and window openings in such car may be closed 20 simultaneously in the event of a person entering the car and attempting to loot the same.

It is also my purpose to provide apparatus of the type set forth whereby the door 25 and window openings of the car may be closed simultaneously and quickly so as to trap the robber therein.

Furthermore, I aim to provide safety apparatus for railway mail cars which will 30 embrace the desired features of simplicity, efficiency and durability, which may be installed and maintained at a minimum expense and which will operate effectively when necessary.

35 With the above and other objects in view, the invention consists in the construction, combination and arrangement of parts hereinafter set forth in and falling within the scope of the claim.

40 In the accompanying drawings; Figure 1 is a longitudinal sectional view through a railway mail car equipped with safety apparatus constructed in accordance with the present invention. Fig. 2 is a horizontal 45 sectional view therethrough. Fig. 3 is a transverse sectional view through the car.

Referring now to the drawings in detail, 1 designates the body of a railway mail car having the opposite side walls thereof 50 formed with door openings 2 and window openings 3 appropriately spaced apart along the respective walls of the body and adapted

to be closed through the medium of sliding doors and windows, as usual.

Formed in one end wall of the car body 55 is a door opening 4 adapted to be closed by means of the usual sliding door. As usual, the side and end walls of the car body are formed of inner and outer sections having the confronting faces thereof spaced apart 60 to form an air space.

Disposed between the sections of each side wall of the car body above the door and window openings therein and extending longitudinally thereof is a track rail 5, while 65 disposed between the sections of the end wall formed with the door opening 5 above such opening is a horizontal track rail 6 having the opposite ends thereof terminating contiguous to the adjacent ends of the 70 track rails 5.

Slidably mounted upon each track rail 5 are carriages 7 corresponding in number with the openings in the adjacent side wall of the car and each comprising a pair of 75 vertically disposed arms 8 spaced apart and having the upper extremities thereof forked to receive the track rail.

Journaled in the forked extremities of the arms 8 are rollers 9 disposed above the 80 track rail and resting on the upper edge thereof to support the arms 8 and permit the latter to slide along the track rail with the least friction.

Formed integral with the arms 8 of the 85 carriages 7 adjacent to each door opening 2 or otherwise connected thereto and depending therefrom is a closure which, in the present instance, is in the form of a plate 10 corresponding in dimensions with the dimensions of the adjacent door opening so that when the carriage is moved in one direction along the trackway the plate will slide across the door opening and so obstruct the same.

90 Formed integral with or otherwise connected to the arms 8 of the carriages 7 adjacent to the window openings 3 in each side wall and depending from such arms are closures 11 preferably, although not necessarily, in the form of plates and capable of longitudinal sliding movement in one direction to obstruct the window openings and in the opposite direction to open the same. Slid-

ably mounted upon the track 6 is a carriage 12 identical in construction to the carriages 7 and connected with the lower ends of the arms of the carriage 12 is a closure plate 13 capable of movement to obstruct the door opening 4.

The plates 10 and 11 in each side wall of the car body are connected to one another so that the same will move to open and closed positions simultaneously and in the present instance, the lower edges of the plates 11 in each side wall are fastened to a horizontal rod 14 and one end of such rod secured to the rear edge of the adjacent door plate 10 as at 15.

Connected with the carriage 7 of the rear window plate 11 in one side wall of the body is a cord 16 or other flexible element trained over a guide sheave 17 suitably fastened between the sections of the particular side wall of the car at the juncture of such side wall with the end wall, the free end of the cord or chain 16 being connected with the carriage 12 carrying the door 13 so that when the plates 10 and 11 are moved to closed positions, the carriage 12 will be actuated along the track 6 to slide the plate across the door opening 4 and so close the latter.

Connected with the rear end of the carriage 12 is one end of a chain 18 or other flexible element having the opposite end thereof trained over a guide sheave 19 and equipped with a weight 20 depending therefrom and working within a casing 21, the weight 20 acting to restore the plate 13 to normal position when the plates 10 and 11 are similarly actuated.

In the present instance, the actuating mechanism for the plates 10 and 11 in the opposite side walls of the car body and the plate 13 comprises horizontal rods 22 disposed below the door openings 2 in the side walls of the car and each having one end thereof projecting upwardly as at 23 through a slot 24 formed in the floor of the car at one side of the adjacent door opening. These horizontal rods 22 are mounted for sliding movement in suitable bearings and the upturned end portions 23 thereof are suitably fastened to the respective plates 10, while the remaining ends project upwardly through slots in the floor of the car between the sections of the side walls and are pivotally connected with links 25 which in turn are pivoted to arms 26 fixed to the opposite extremities of an operating shaft 27 journaled in horizontally alining bearings transversely of the car body. This shaft 27 is equipped with an operating handle 28 and is disposed adjacent to the end wall of the body opposite from that formed with the door opening 4.

The interior of the car body 1 adjacent to

the shaft 27 is provided with a transverse 65 partition 29 spaced apart from the shaft 27 and coöperating with the adjacent end wall of the car to form a compartment 30 designed to house a guard comprising one or more persons.

The partition 29 is provided with a suitable door 31 so that the guard may enter and leave the compartment 30 formed with sight holes 32, while the opposite side walls of the compartment formed by the 75 adjacent portions of the side walls of the car body, are formed with sight holes 33.

In practice, a guard composed of any number of persons is placed in the compartment 30 and the door and window openings opened up as usual. Should one or more persons board the car and attempt to loot the same, the guard in the compartment grasps the handle 28 and rotates the shaft 27 thereby swinging the arms 26 in 85 an arc and so exerting a pull upon the links 25 and the rods 22. As the rods 22 slide within their bearings under the action of the shaft 27 the plates 10 and 11 in the opposite sides walls of the car and the plate 90 13 in the end wall of the car are moved to close the respective openings thereby trapping the persons within the car. When the door and window openings are closed, the arms 26 lie in a substantially horizontal 95 plane while the links 25 overlie the shaft 27 and in order to lock the closures in actuated position the under edges of the links 25 are formed with depressions 34 that receive the end portions of the shaft 27 and 100 so hold the closures against opening movement.

From the foregoing description taken in connection with the accompanying drawings, the construction, mode of operation 105 and manner of employing my invention will be readily apparent. It will be seen that I have provided a safety apparatus for railway cars wherein the sliding closures are disposed within the walls of the 110 car and are therefore invisible, while such closures may be quickly actuated to obstruct the door and window openings in the car so as to prevent escape therefrom.

While I have herein shown and described one preferred form of my invention by way of illustration, I wish it to be understood that I do not limit or confine myself to the precise details of construction herein described and delineated, as modification 115 and variation may be made within the scope of the claim without departing from the spirit of the invention.

I claim:

The combination with a car body having 125 door and window openings therein, of closures movable to close said openings, means connecting said closures for simultaneous

movement, horizontal rods connected to said closures, a horizontal actuating shaft journaled transversely of the car body and capable of rotary movement, arms connected to said shaft, links pivoted to the outer ends of said arms and having the remaining extremities thereof pivotally connected to said rods and movable bodily from one side of said shaft to the other in the movement of 5 the shaft whereby the rods will be slid horizontally to actuate said closures to 10

closed positions, said links having grooves in the under edges thereof designed to receive said shaft when the links are actuated to door closing position, and means for 15 actuating said shaft.

In testimony whereof I affix my signature in presence of two witnesses.

BENJAMIN F. WILLIAMS.
